UNITED STATES PATENT OFFICE.

WILLIAM H. DUNKERLEY, OF PATERSON, NEW JERSEY.

BRAIDING-MACHINE.

1,188,741.

Specification of Letters Patent. Patented June 27, 1916.

Application filed July 14, 1914. Serial No. 850,865.

To all whom it may concern:

Be it known that I, WILLIAM H. DUNKERLEY, a citizen of the United States, residing at Paterson, in the county of Passaic and State of New Jersey, have invented a certain new and useful Improvement in Braiding-Machines, of which the following is a specification.

The invention relates to the manufacture of automobile tires and shoes and analogous annular articles having a continuous slit or opening along the inner circumferential face, and the main object of the invention is to provide a machine by which such articles may be braided on an annular core in the same form they assume in service.

Another important object is to provide means for producing a uniform selvage along each margin of such slit, and holding such selvage in place upon the core, and a further object is to provide means for incorporating in such selvages strengthening or shape-retaining cords or wires, introduced during the braiding operation.

The invention consists in certain novel features of construction and arrangement by which the above objects are attained, to be hereinafter described and claimed.

The accompanying drawings form a part of this specification and show the invention as it has been carried out in practice.

Figure 1 is a side elevation of certain portions of a braiding machine constructed in accordance with the invention. Fig. 2 is a corresponding plan view partly in horizontal section. Fig. 3 is a plan view of the selvage device alone, on a larger scale. Fig. 4 is a corresponding side elevation. Fig. 5 is a central vertical section taken on the line 5-5 in Fig. 3, and partly in elevation. Fig. 6 is a corresponding plan view of the under face. Fig. 7 is a front view. Fig. 8 is a horizontal section through a tire and its removable core, showing certain portions of the selvage device in plan view, on a still larger scale. Fig. 9 is a cross-section on the line 9-9 in Fig. 8, showing a detail. Fig. 10 is a side elevation partly in vertical section, showing a portion of the guide for delivering the strengthening wire to the selvage.

Similar letters of reference indicate the same parts in all the figures.

A is the bed or table of a braiding machine, only partially shown, equipped with dolls or braiding carriers B B in the ways a, and means, not shown, for traversing the

carriers along their serpentine paths in such ways as usual. The bed is open in the center and has an opening or channel at A¹ through which the completed annulus or tire and its core may be removed.

C is a collapsible annular form or core standing vertically in the central opening and channel with its inner limb centrally located at the braiding line and supported on grooved rollers A² A² below, one of which is driven by suitable mechanism, not shown, to revolve the core slowly in the direction indicated by the arrow as the covering is braided thereon, and held in the upright position by a similar roller A³ above, yieldingly mounted in a housing A⁴ on a fixed bracket A⁵, and adapted to rise as the continuous braided coverings are successively applied and the tire or annulus correspondingly increases in size. The braiding carriers apply the covering M thereon except along a line on the inner circumferential face, thus providing the usual narrow slit or opening for the insertion of an inner tube. Obviously the edges of such braided fabric will not hug the core C during the process of manufacture unless maintained in position while such edges or selvages are being braided. The device to be described thus holds the selvages during their formation and also incorporates a cord or wire therewith by which the selvages are subsequently maintained.

A⁶ is an arm adjustably mounted on the bracket A⁵ and extending downward along side the core toward the braiding line; it carries at its end a platform made in two portions E E¹ on the under face of which are pivoted two plates F¹ F² each the counterpart of the other and each having a segmental toothed portion F³ presented toward the other. These segmental gears mesh with a screw or worm F between them, mounted in lugs on the portion E of the platform and provided with a head F⁴ by which it may be turned to rotate the plates F¹ and F² partially and in opposite directions.

Each plate has a pair of outwardly projecting arms G and H arranged one above the other as shown, with an open space f between them, and each upper arm G carries a vertically mounted spur-wheel G¹ having a series of sharp radial pins adapted to engage the selvage of the fabric at or a little above the braiding line and hold such selvages against spreading laterally one from the other. The spur-wheels revolve on

their studs g as the core with its covering is fed slowly upward at the braiding line, and the teeth remain engaged while the selvages are being formed, thus insuring the 5 maintenance of their position on the core.

To guide the selvage threads and aid in laying them correctly in the fabric at the braiding point, a post J is mounted at the center of each of the terminal islands $A^7 A^7$ 10 of the race-ways, around which the carriers pass successively in reversing their travel, and each post carries a rod, marked J^1 and J^2 respectively, extending angularly upward from its post, with its free end extending through the space f and presented adjacent to one of the spur-wheels G^1 near the braiding line of the selvage and serving as a guide for the marginal threads, which as the carriers traverse the terminals of the 15 raceways, are received and slide upon the smooth surfaces of the rods and are delivered by the latter directly at the braiding point.

To strengthen the selvages and thicken 20 the tire or shoe along such margins, heavy filaments are introduced preferably in the form of wires N drawn from spools or reels, not shown, beneath the bed and each passing upwardly through one of the terminal 25 islands $A^7 A^7$, over a grooved pulley J^3 mounted on the post J , thence alongside its rod J^1 or J^2 and through a tubular guide J^4 near the end of such rod, passing beneath such end and under a grooved pulley or 30 wheel G^2 on the inner face of the spur-wheel G^1 and thence to the fabric on the line of the selvage where it is braided in or 35 enclosed by the selvage threads.

In order to support the free end of each 40 rod, such end lies upon a wheel H^1 preferably grooved, each mounted below and at a slight distance within the inner face of the adjacent spur-wheel G^1 , so that outward strains tending to separate further the ends 45 of the rods, due to the pull of the threads, are resisted by the contact of the rod-ends with the spur-wheels. The latter overlap the wheels H^1 slightly but sufficient space between each spur-wheel G^1 and its grooved 50 wheel H^1 is provided to permit the threads to pass.

The two portions E and E^1 of the platform are joined by a studbolt E^2 extending through a vertical slot e in the lug E^3 on 55 the portion E^1 into the lug E^4 on the portion E , so that by loosening the bolt the portion E^1 may be removed with its plate and wheels to permit the withdrawal of the tire and its core from the machine through the channel 60 A^1 in the table; and the rod J^2 is mounted in a rotatable head J^4 on its post J , so that it may be swung outwardly out of the way when released by the removal of the portion E^1 of the platform.

65 By turning the worm F the plates F^1 and

F^2 may be partially rotated and the pairs of wheels $G^1 H^1$ and $G^1 H^1$ brought nearer together or farther separated as desired to correspond to the width of space desired between the selvages. In Figs. 3 to 7 inclusive the separation is shown for convenience of illustration as abnormally great; the wheels $G^1 G^1$ in Fig. 8 are more nearly correctly positioned relatively to each other and to the core and tire. 75

As many thicknesses or plies may be braided as desired, the covering being applied continuously and the selvage wires $N N$ being similarly supplied and incorporated. Suitable treatment with rubber and subsequent vulcanization produces a tire in which all the threads occupy exactly the positions assumed in the braiding operation, consequently all are subjected to uniform strains when the tire is inflated. 80

The wired selvages are extremely strong and well adapted to be grasped and held by the wheel-rim. 85

Modifications may be made in the form and proportions of the various parts without departing from the invention, and parts may be used without the whole. The wheels H^1 may be omitted, depending upon the stiffness of the rods $J^1 J^2$ aided by the adjacent faces of the spur-wheels G^1 to 90 maintain them in the required positions. Any suitable means for supporting and rotating the core C may be employed. Instead of the wire N , a group or cord of small wires or a cord of any suitable material may be 95 employed.

I claim:—

1. In a braiding machine, a table having a central opening and raceways partially encircling such opening, braiding carriers 105 in such raceways, means for supporting and rotating an annular core in such opening, said carriers arranged to braid an annulus upon said core with selvages on its inner face, means arranged to engage such selvages and hold the latter in place on said core during the braiding operation, and means terminating adjacent said first-named means for guiding the selvage threads and laying them in the fabric disengaged from 110 said last-named means.

2. In a braiding machine, a table having a central opening and raceways partially encircling such opening, braiding carriers 115 in such raceways, means for supporting and rotating an annular core in such opening, said carriers arranged to braid an annulus upon said core with selvages on its inner face, and means arranged to engage such selvages and hold the latter in place on said core during the braiding operation, and means for adjusting said holding means. 120

3. In a braiding machine, a table having a central opening and raceways partially 125 encircling such opening, braiding carriers

in such raceways, means for supporting and rotating an annular core in such opening, said carriers arranged to braid an annulus upon said core with selvages on its inner face, rotatable toothed means adapted to engage such selvages and hold the latter in place on said core during the braiding operation and means terminating adjacent said toothed means for guiding the selvage threads and laying them in the fabric disengaged from said guiding means.

4. In a braiding machine, a table having a central opening and raceways partially encircling such opening, braiding carriers in such raceways, means for supporting and rotating an annular core in such opening, said carriers arranged to braid an annulus upon said core with selvages on its inner face, rotatable toothed means adapted to engage such selvages and hold the latter in place on said core during the braiding operation, and means for adjusting said toothed means and thereby varying the distance between said selvages.

5. In a braiding machine, a table having a central opening and raceways partially encircling such opening, braiding carriers in such raceways, means for supporting and rotating an annular core in such opening, said carriers arranged to braid an annulus upon said core with selvages on its inner face, a pair of spur-wheels each adapted to engage one of said selvages and hold the latter against separation from each other during the braiding operation and means terminating adjacent said spur-wheels for guiding the selvage threads and laying them in the fabric disengaged from said guiding means.

6. In a braiding machine, a table having a central opening and raceways partially encircling such opening, braiding carriers in such raceways, means for supporting and rotating an annular core in such opening, said carriers arranged to braid an annulus upon said core with selvages on its inner face, means adapted to engage such selvages and hold the latter in place on said core during the braiding operation, and means for guiding the selvage threads from said carriers to the braiding line and means on said guiding means for supporting and guiding a selvage reinforcing element.

7. In a braiding machine, a table having a central opening and raceways partially encircling such opening, braiding carriers in such raceways, means for supporting and rotating an annular core in such opening, said carriers arranged to braid an annulus upon said core with selvages on its inner face, means adapted to engage such selvages and hold the latter in place on said core during the braiding operation, and means for guiding the selvage threads and a selvage reinforcing element.

8. In a braiding machine, a table having a central opening and raceways partially encircling such opening, braiding carriers in such raceways, means for supporting and rotating an annular core in such opening, said carriers arranged to braid an annulus upon said core with selvages on its inner face, a pair of spur-wheels each adapted to engage one of said selvages and hold said selvages against separation from each other during the braiding operation, and means for adjusting said spur-wheels and thereby varying the distance between said selvages.

9. In a braiding machine, a table having a central opening and raceways partially encircling such opening, braiding carriers in such raceways, means for supporting and rotating an annular core in such opening, said carriers arranged to braid an annulus upon said core with selvages on its inner face, a platform, plates pivotally mounted thereon, each of said plates having a toothed segment, a worm in mesh with said segments, arms on said plates, and spur-wheels on said arms adapted to engage said selvages and hold the latter in place on said core during the braiding operation.

10. In a braiding machine, a table having a central opening and raceways partially encircling such opening, braiding carriers in such raceways, means for supporting and rotating an annular core in such opening, said carriers arranged to braid an annulus upon said core with selvages on its inner face, adjustable means arranged to engage such selvages and hold the latter in place on said core during the braiding operation, and rods extending from the terminals of such raceways to the braiding line for guiding the selvage threads.

11. In a braiding machine, a table having a central opening and raceways partially encircling such opening, braiding carriers in such raceways, means for supporting and rotating an annular core in such opening, said carriers arranged to braid an annulus upon said core with selvages on its inner face, means arranged to engage such selvages and hold the latter in place on said core during the braiding operation, rods extending from the terminals of such raceways to the braiding line for guiding the selvage threads, and means for swinging one of said rods to permit the removal of said core and annulus.

12. In a braiding machine, a table having a central opening and raceways partially encircling such opening, braiding carriers in such raceways, means for supporting and rotating an annular core in such opening, said carriers arranged to braid an annulus upon said core with selvages on its inner face, a platform, plates pivotally mounted thereon, each of said plates having

- a toothed segment, a worm in mesh with said segments, arms on said plates, and spur-wheels on said arms adapted to engage said selvages and hold the latter in place on said core during the braiding operation, said platform comprised of two portions one of which is removable to permit the removal of said core and annulus.
13. In a braiding machine, a table having a central opening and raceways partially encircling such opening, braiding carriers in such raceways, means for supporting and rotating an annular core in such opening, said carriers arranged to braid an annulus upon said core with selvages on its inner face, a platform, plates pivotally mounted thereon, each of said plates having a toothed segment, a worm in mesh with said segments, arms on said plates, spur-wheels on said arms adapted to engage said selvages and hold the latter in place on said core during the braiding operation, said platform comprised of two portions one of which is removable to permit the removal of said core and annulus, posts set in the terminal islands of such raceway, rods

mounted on said posts and extending to said spur-wheels at the braiding line, and wheels adjacent to and below said spur-wheels arranged to serve therewith in supporting the free ends of said rods.

14. In a braiding machine, a table having a central opening and raceways partially encircling such opening, braiding carriers in such raceways, means for supporting and rotating an annular core in such opening, said carriers arranged to braid an annulus upon said core with selvages on its inner face, means arranged to engage such selvages and hold the latter in place on said core during the braiding operation, a post set in one of the terminal islands of such raceway, a rotatable head on said post, and a rod extending from said head to the braiding line on said core.

In testimony that I claim the invention above set forth I affix my signature, in presence of two witnesses.

WILLIAM H. DUNKERLEY.
